CLUTCH PENCIL

Günter Fuchs, Schwarzenbach, Saale, Germany, assignor
to A. W. Faber-Castell, Stein, near Nurnberg, Germany

Filed Nov. 10, 1958, Ser. No. 53,329

Claims priority, application Germany May 10, 1958

Term of patent 14 years

(Cl. D74—24)

FIG. 2.

FIG. 1.

FIG. 3.

FIGURE 1 is a front elevational view of a clutch pencil showing my new design;

FIGURE 2 is a top plan view; and

FIGURE 3 is a bottom plan view thereof.

The essential features of my design reside in the portions shown in solid lines on the drawing.

I claim:

The ornamental design for a clutch pencil, as shown and described.
